WINDING STEM

Henri Edmond Vermot, Lancaster Township,
Lancaster County, Pa., assignor to Hamilton
Watch Company, Lancaster, Pa.

Application October 10, 1951, Serial No. 250,741

1 Claim. (Cl. 58—63)

1

This invention is directed to an improved winding stem for watches.

The object of the invention is to provide a one piece winding stem which may be held to permit the crown to be assembled or removed without the use of special tools.

Heretofore, where a watch is cased in a solid back case and the movement is inserted from the dial side, it is necessary to have a two piece stem in order to be able to insert the movement without damaging the stem. With the two piece stem it is necessary to increase the distance from the edge of the movement to the inside rim of a case, thus making it necessary to have a larger watch.

It is the object of the present invention to provide a one piece stem which having been affixed to the movement may be inserted in the opening of a solid back case and the crown afterwards affixed to the threaded end of the stem.

It is a further object of the present invention to provide a collar on said stem having flattened opposed surfaces which may be engaged by any ordinary jeweler's tool, such as a screw driver, so that the stem may be firmly held to attach or remove the crown.

The invention is shown in the accompanying drawing in which:

Figure 1 is an enlarged perspective view of the stem.

Figure 2 is an enlarged view showing the function of the flattened opposed surfaces.

Figure 3 is a perspective view of the particular type of watch-case to which the invention is applicable.

Referring particularly to the drawing, the winding stem for a watch is formed with the ordinary screw threaded end 5 for the reception of the crown. The other end of the stem is formed with a bearing 6, a squared section 7 for the reception of the clutch and the winding arbor, a collar 8 and bearing 9.

Adjacent the bearing 9 a collar 10 is formed with two flat opposed sides 11. The crown 12 is threaded on the end 5 until it abuts the tip 13. This crown must be turned tightly on the screw threaded end 5 so that the watch may be set in a counter-clockwise motion and to permit the back turning of the crown during the winding operation without turning the crown off the stem. It would be, of course, possible to turn

2

the crown on the threaded end 5 until the mainspring was completely wound, and using the wound mainspring as a stop to continue turning the crown until it engaged the tip 13. This, however, would put a tremendous strain on the winding gears and the mainspring which would probably rupture one or the other before the crown was tightened sufficiently. It is, therefore, necessary in a one piece stem that some means be provided to securely hold the stem while the crown is threaded thereon. The forming of the flats 11 on the collar 10 permits the insertion of a screw driver 14 within a slot 15 of the case 16, the screw driver binding against the edge 17 of the slot and the flat side 11 of the collar 10. Figure 2 shows the screw driver inserted to hold the stem to permit removal of the crown. This construction permits the crown to be securely tightened on the stem without the addition of special tools for holding the stem and allows the dial 18 to be brought closer to the upstanding rim 19 of the case 16, thus permitting an overall smaller watch.

Referring particularly to Figure 3 a watch-case 16 of the type used with this one piece winding stem is shown. The watch-case is formed with a solid back, an upper rim 19 and a movement supporting annular shoulder 20. A hole 21 formed in the side permits the insertion of the one piece winding stem while lugs 22 receive a strap or band.

What is claimed is:

The combination of a watch-case with a one piece winding stem, said case being formed with a solid back and an unbroken rim and with a well between the edge of the dial and the rim of the case, said winding stem being formed with a collar projecting into said well, said collar having flat opposing surfaces whereby a screw driver may be inserted between the edge of the well and one of the flat surfaces of the stem to prevent the stem from turning.
